UNITED STATES PATENT OFFICE

ALBERT R. GOLRICK, OF CLEVELAND, OHIO, ASSIGNOR TO THE FOOTE-BURT COMPANY,
OF CLEVELAND, OHIO, A CORPORATION OF OHIO

WORKHOLDING MECHANISM

Application filed July 23, 1928. Serial No. 295,870.

The object of this invention is to provide mechanism for holding a blank in cooperative relation to a tool arranged to act thereon.

A specific object is to provide an improved 5 holder for nut blanks or the like, which will hold the blanks with their apertures in alignment with a tap, irrespective of variations in the relation of such apertures to the outside surfaces of the blanks.

10 Further objects and features of the invention will become apparent from the following description relating to the accompanying drawings, wherein I show my preferred form. The essential characteristics are summarized 15 in the claims.

In the prior patent to Daniel Kelleher No. 1,645,285, there is shown an automatic tapping machine with which, for example, my mechanism is adapted for use. The Kelleher 20 patent shows holders for cylindrical conduits and hexagonal nut blanks to be internally threaded. When such machines are operated at very high speeds there is more or less likelihood of breaking the tap, because of irregularities between the blank openings and the 25 outside surfaces thereof, for example, the hexagonal faces of a nut. This is mainly because in ordinary holders, the holding surfaces are fairly close to the blank on all sides, and if an aperture in a blank about to be 30 tapped is unusually eccentric, the tap already threaded through several true centered blanks has to bend to enter the eccentric aperture. In the embodiment of my invention shown, provision is made to hold the blanks with the apertures in true alignment 35 with the tap, irrespective of eccentricity of the apertures in some of the blanks.

In its preferred form, the mechanism comprises a holder having a longitudinal bore into which the blanks are fed endwise, the tap being brought up into cooperation with paired blanks in a given position in the holder. The holder, as shown, is arranged to receive two new blanks at a time. The blank

positioning mechanism comprises a blank aligning and advancing bar, and the securing mechanism a plurality of yieldingly mounted fingers arranged to engage the blanks at various points. Prior to beginning of the tapping operation on the newly positioned blanks, the fingers are arranged to be clamped or locked in place. A further refinement consists in positively releasing the fingers to permit free ejection of the tapped blanks 50 when the tapping operation is substantially completed.

In the drawings, Fig. 1, 2 and 3 are sectional views showing a work holder, a tap, and blank feeding mechanism, each view 55 showing the above elements in different relationships; Fig. 4 is a cross sectional fragmentary view taken substantially along the line 4-4 of Fig. 3; Fig. 5 is a fragmentary 60 sectional plan view, taken substantially along the line 5-5 on Fig. 1, the tap being omitted and some of the parts being shown in positions different from Fig. 1; Figs. 6, 7 and 8 are fragmentary cross sectional views 65 through different portions of the work holder, as indicated by corresponding lines on Fig. 5; Fig. 9 is a sectional bottom plan view 70 of the mechanism for causing the fingers to be clamped in place when in engagement with blanks, Fig. 10 is a perspective view of a 75 clamping part associated with the finger clamping mechanism.

Referring in detail to the drawings, the tap T (Fig. 1) is arranged to be automatically engaged and rotated by suitable spindle 80 mechanism, such as shown in the Kelleher patent, a suitable chuck element for association with such spindle mechanism being shown at 1. 2 designates a work holder in which blanks, such as W, are placed and held 85 for tapping. The work holder has a longitudinal bore 3 parallel to the axis of movement of the tap. The shape of the bore is determined by the shape of the blanks, for example, if the blanks are hexagonal nuts, the

interior of the bore will be hexagonal to prevent rotation of the blanks, while in the holder. 5 designates a rigid portion of the machine arranged to support a longitudinally 50 slidable feed bar 6, the end of which carries new blanks, as from a position at W¹, into the work holder. The blanks may be fed from a suitable raceway in the nature of a tube 8. As shown, the blanks are advanced 10 two-abreast successively into the path of the member 6.

In the prior application of Daniel Kelleher, Serial No. 227,677, filed October 21, 1927, there is shown a more refined mechanism for 15 feeding nut blanks, two at a time, but since the feeding forms no part of the present application, it may be stated that this, or any suitable feeding means, may be used.

The Kelleher machine is governed by a 20 master cam which has cam members operating on a master control rod, which not only brings the chuck up to the tap and causes it to engage the tap, but also operates in timed relation to such chucking to cause the reciprocation of a feed bar, such as 6, herein 25 shown, to cause it to draw away from a raceway, such as 8, to permit the work to drop in front of the feed bar in substantial alignment with the tap. Afterwards, the return movement of the feed bar carries the new work 30 into the work holder and simultaneously moves the tap, already threaded through previously tapped work, to a position to start tapping.

35 Such master cam may also control a plunger, such as herein shown at 10, Figs. 1 to 4, the plunger being arranged to hold two pairs of pieces of work in separated relation, while being tapped. The plunger, as shown, may 40 be operated by a rock shaft 15, suitably supported on the machine in brackets, not shown, and connected as by an arm 16 to the plunger 10, there being a spring 17 to force the end of the plunger downwardly between the pairs 45 of pieces. The rock shaft may be operated from an eccentric portion 18 of the cam, shown in broken lines at 19, as by reason of a cam follower arm 20.

Starting with Fig. 1, the operation of the 50 machine will be first considered as having been brought to a period in its cycle at which the work blanks W are said to be finished. As in the Kelleher machine, the tap having advanced with relation to work sufficiently to 55 have pushed back the feed bar 6, a new cycle of operation will start in which the feed bar is first withdrawn by the master cam to a position, such as shown in Fig. 2. In this 60 position two new pieces of work drop from their position as at W' in the raceway into alignment with the bar as at W''. In the end of the bar 6 is slidably carried a work aligning plunger 25 acted on by a spring 26 and prevented from outward movement past 65 the position shown in Fig. 2 by a threaded

ring 27. Continuation of the cycle of operation now causes the return movement of the feed bar 6 (to the left as shown) to position the work in the work holder. As the bar returns the plunger 25 is inserted in the apertures of the blanks substantially fitting the same and aligning the apertures with the tap. 70

It will now be seen that if the outside surfaces of either or both of the two blanks, are not in parallel relation to the apertures in the blanks, or the apertures are eccentric, these blanks will be cocked on the plunger, as in Fig. 3, or displaced bodily, as the case may be. As the new pieces of work are thus advanced, the plunger 10 is withdrawn to allow 75 the oncoming pieces to push the tap back, as in Fig. 3. Afterward the plunger comes from between the two pairs of pieces of work, the chuck takes hold of the tap and the cycle is 80 repeated.

To hold the cocked or bodily displaced pieces in alignment with the tap as the tap now advances, I propose to provide a plurality of slidable fingers, such as 30, Figs. 5, 6, 7 and 8. The fingers as shown, are offset outwardly in the holder member 2, as at 31, Fig. 5 to provide space for clamping screws 33. These screws may be of the character shown in Fig. 6 wherein one of the screws is shown as having a head 34 above the holder and engaging thereagainst, the lower end being threaded, as at 35, for engagement with a threaded block 36 arranged to engage the lower surfaces of the two lowermost fingers simultaneously. As shown, one of the screws has right hand threads and one has left hand threads. One screw may be rotated to the right and one to the left automatically, just as a pair of blanks reach start tapping position in the holder. The clamping reaction of the member 36 on the lowermost fingers may be transmitted to the uppermost fingers through a loose block 37 between the upper and lower fingers at each side, i. e. one of these blocks being associated with each screw but vertically slidable relative thereto. Each of the fingers 30 is provided with a light spring, designated 40, bearing against the rear ends thereof and arranged to force the fingers against the blanks, while still on the aligning plunger 25, in substantially the position shown in Fig. 5. The springs react against side closure plates 2' of the holder. 100

For operating the clamping screws, I preferably provide a toggle arrangement, Fig. 9, wherein there are a pair of arms 42 rigidly attached to respective screws, the arms being substantially alike and having slots 43. Engaging the slots is a pin 45 carried in the arms of a bifurcated member 46 arranged to be shifted by a bar 47. Means for shifting the bar to cause the screws 33 to clamp, may comprise a pin 50 adapted to engage an abutment member 51 slidably and yieldingly 105 110 115 120 125 130

mounted in the slotted end of the bar 47. The force exerted by the movement of the pin may be transmitted to the bar through a spring 52. As shown, the pin 50 is carried on an arm 55 which is connected to the main control rod (not shown), for advancing the plunger 6 to feed the work. As shown, this arm 55 operates yieldingly against the feed bar 6, in the direction to feed the blanks, by reason of a spring 57 reacting at one end on the arm and at the other on an abutment or collar 58 rigid on the feed bar. This collar is arranged to engage the frame part 5 at a time when the two blanks are positioned adjacent the plunger 10, and thereafter, further movement to the left, (Fig. 3) of the arm 55 causes the pin 50 to operate the toggle arms 42 to cause the clamping rotation of the screws 33, as above described.

With the fingers in engagement with the blanks at W, the oncoming tap will be started in true alignment with the openings in each blank, and will therefore not be likely to be broken because of the shifting of the blanks after the threading operation has started.

In order to remove the fingers before the blanks are ejected, as by movement from the position at one side of the plunger 10 to the other, I may provide a device, such as shown in Fig. 7, comprising a U-shaped member 60 having downwardly extending arms 61 provided with cam surfaces 62 for bearing against respective shoulders 63 of the fingers. This U-shaped member may be drawn upwardly as by an arm 65 on the rock shaft 15 at the time when the rock shaft operates to withdraw the plunger 10 from the nuts.

It will be understood that the rock shaft 15 operates in timed relation to the reciprocation of the work position bar 6 in a machine for tapping blanks, such as shown in the Kelleher patent mentioned.

I claim:

1. In mechanism of the class described, a work holder recessed to receive blanks to be operated upon by a tool, and a plurality of resiliently biased rigid members arranged to approach the work in the holder from a plurality of directions, together with means for simultaneously locking said members in work holding position.

2. In mechanism of the kind described, a longitudinally recessed work holder, a tool adapted to enter the recess and operate on the work by a rotational and advancing movement, a work positioning device adapted to approach the work holder to position work therein endwise of the recess, yielding means carried by said device and arranged to align work with the tool, and other means arranged to engage the work when positioned in the holder to maintain the work in alignment with the tool.

3. In mechanism of the kind described, a

longitudinally recessed work holder, a tool arranged to enter the holder, a work positioning device, including a yielding member arranged to approach the holder and position work therein, a plurality of individually movable, disconnected fingers, and means to cause the fingers to engage the positioned work, there being clamping means arranged to simultaneously act on a plurality of such fingers to hold the fingers in work positioning relation.

4. In mechanism of the class described, a longitudinally recessed work holder, a tool adapted to enter the work holder to act on work therein, a work positioning device for apertured work blanks including a bar and a relatively movable plunger yieldingly supported by the bar and arranged to enter the apertures in the work, said bar being shouldered to shift the work into the holder, and means carried by the holder and arranged to approach the work from opposite directions to hold the same in tool engaging position, there being means actuated by said bar for locking the last mentioned means in work holding position.

5. In mechanism of the kind described, a work holder, a tool arranged to act on work held thereby, shiftable means arranged to convey work to the holder, resiliently biased means for holding such advanced work in cooperative relation to the tool, and means actuated by said work advancing means and arranged to lock said resiliently biased means in work holding position.

6. In work performing mechanism means to initially position a piece of work, a plurality of resiliently biased members guided to engage the work at a plurality of points to hold the work, the means rendered active by the operation of the positioning means to lock such plurality of members in work holding position.

7. In mechanism of the kind described, a work holder, independently movable members arranged to engage a blank in said holder, yielding means to cause such engagement of the members with the blank and means to simultaneously lock all the members in various relationships as determined by variations in the blank.

8. In a work holding device, a plurality of independently movable resiliently biased members arranged to approach the work from opposite directions, and means to substantially simultaneously lock said members in work engaging position.

9. In a tapping mechanism, a head having a work holding recess, means to move work into said recess, resiliently biased means arranged to engage the work in said recess and capable of being rigidly locked to hold the work in tapping position, and means operating in timed relation to the operation of the first named means to rigidly lock said re-

silently biased means in work holding position.

10. In a tapping machine, a head having a work holding and tap receiving recess extending thereinto; means to move work into said recess, resiliently biased means arranged to engage the work in said recess and capable of rigidly holding the work in tapping position, and means connected with the first named means and operated thereby to lock said resiliently biased means in work holding position.

In testimony whereof, I hereunto affix my signature.

16 ALBERT R. GOLRICK.
